UNITED STATES PATENT OFFICE.

ROBERT C. KAHRMANN, OF ELIZABETH, NEW JERSEY, ASSIGNOR TO HAMPDEN GLAZED PAPER & CARD COMPANY, OF HOLYOKE, MASSACHUSETTS, A CORPORATION OF MASSACHUSETTS.

DESIGN FOR A COVER PAPER OR THE LIKE.

Application filed May 2, 1928. Serial No. 26,526. Term of patent 3½ years.

To all whom it may concern:

Be it known that I, ROBERT C. KAHRMANN, a citizen of the United States of America, residing at Elizabeth, county of Union, and State of New Jersey, have invented a new, original, and ornamental Design for Cover Paper or the like, of which the following is a specification, reference being had to the accompanying drawing, forming a part thereof.

per or the like embodying my new and ornamental design.

The design is intended to be employed in repetition over the surface of the paper, the repeat unit being indicated by arrows in the drawing.

I claim:

The ornamental design for cover paper or the like as shown and described.

ROBERT C. KAHRMANN.
